(57) **CLAIM**

I claim the ornamental design for a pair of LED strips and power pack, as shown and described.

DESCRIPTION

FIG. 1 is a perspective view of a pair of LED strips and power pack, showing my new design in a deployed configuration; FIG. 2 is a perspective view thereof, illustrated in a straight configuration;

FIG. 3 is a top plan view of FIG. 2;

FIG. 4 is a bottom plan view of FIG. 2;

FIG. 5 is a right-side elevational view of FIG. 2;

FIG. 6 is a left-side elevational view of FIG. 2;

FIG. 7 is a front elevational view of FIG. 2;

FIG. 8 is a rear elevational view of FIG. 2;

FIG. 9 is an enlarged, partial perspective view taken along line 9 of FIG. 1;

FIG. 10 is an enlarged, partial perspective view taken along line 10 of FIG. 2;

FIG. 11 is an enlarged, partial top plan view taken along line 11 of FIG. 3;

FIG. 12 is an enlarged, partial right-side elevational view taken along line 12 of FIG. 5; and,

FIG. 13 is an enlarged, partial front elevational view taken along line 13 of FIG. 7.

The broken lines showing a bicycle helmet in FIGS. 1 and 9 depict environmental matter and form no part of the claimed design.

1 Claim, 8 Drawing Sheets
